UNITED STATES PATENT OFFICE.

EDWARD TIMOTHY FORD AND FRANK FORD WASSAM, OF DUNKIRK, INDIANA.

RAIL-FASTENING DEVICE.

No. 906,403.

Specification of Letters Patent.

Patented Dec. 8, 1908.

Application filed August 3, 1908. Serial No. 446,725.

To all whom it may concern:

Be it known that we, EDWARD TIMOTHY FORD and FRANK FORD WASSAM, citizens of the United States, residing at Dunkirk, in the county of Jay and State of Indiana, have invented certain new and useful Improvements in Rail-Fastening Devices; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in railway fastening devices and the object in view is to produce a simple and efficient and secure means for fastening rails to metallic ties, and comprises various details of construction, combinations and arrangements of parts which will be herein-after fully described and then specifically defined in the appended claims.

Our invention is illustrated in the accompanying drawings, in which:—

Figure 1 is a perspective view showing the application of our invention to the rails and ties of a railway. Fig. 2 is a longitudinal section through a portion of the tie and transversely through the rail and connections. Fig. 3 is a cross sectional view through the tie and connections. Fig. 4 is an enlarged detail view of one of the plates upon which the rail rests. Fig. 5 is an enlarged detail view of one of the locking members.

Reference now being had to the details of the drawings by letter, A designates a metallic tie having a flange B, and a web portion which is provided with apertures B', and apertures C are formed vertically through the flange, one upon either side of the web.

D designates a block having bolts D' projecting through the apertures C, each of which bolts being provided with a transverse aperture d. Said bolts are adapted to pass through the apertures C, and cotter pins E are inserted through the apertures d and serve to securely hold the plates upon the ties. The upper surface of each block D is provided with transverse grooves F which are parallel to each other and each of said grooves has a shoulder portion F'. The flange G of the rail G' is adapted to rest upon the block D or, in the event of the ends of

two meeting rails coming together upon a tie, both rails would rest upon the block D with the flanges of the rails overhanging the grooves F, as shown in the sectional view of 60 the drawings.

H—H designate rail securing members which are of the general shape shown in the drawings, each having a grooved arm H' with a shoulder H² adapted to engage the 65 groove F and each of said members H is provided with a cotter pin E which is adapted to pass through the aperture in a bolt D' and also through the aperture B' in the web of the tie, thereby securely holding the block upon 70 the upper surface of the tie. A cotter pin is preferably then inserted through the end of the cotter pin E to hold the member H in place. It will be noted that said member H has a widened portion I' at the inner end of 75 the finger I, one surface of which widened portion is inclined to conform to the inclined under surface of the flange of the tie with which it contacts when adjusted in place. Projecting from the rail securing member is a 80 lug T which, when the same is applied to a rail, extends down and serves as means for preventing the tie from moving longitudinally as the soil in which the tie is embedded will serve to hold the member and tie from 85 moving. It will be noted that the fastening members H securely hold the blocks and rails to the ties and are so arranged that, when it is desired to remove the rail, it may be easily and quickly done by simply first detaching 90 the locking members H, after which the rails may be removed and also the blocks if desired.

From the foregoing, it will be noted that, by the provision of a fastening means for 95 railway rails as shown and described, a secure locking mechanism is afforded and so constructed that the parts are interchangeable and that the rails will be securely held against accidental displacement.

What we claim to be new and desire to secure by Letters Patent is:—

1. A fastening device for railway rails comprising, in combination with a tie having apertures in the web portion thereof, a 105 grooved block upon the tie and upon which a rail is adapted to rest, a locking member engaging said groove and flange of the rail and having a portion thereof passing through the aperture in the web of the tie, as set forth.

2. A railway rail fastening device comprising a tie having apertured flange and web

portions, a grooved block mounted upon said tie, fastening means secured to the block and passing through apertures in the flange, a locking member engaging the groove of said block and adapted to extend over the flange of a rail upon the block and having a portion thereof passing through the flange of the tie and engaging the fastening means of the block which passes through the flange of the tie, as set forth.

3. A means for fastening railway rails to ties comprising, in combination with a tie having apertured flange and web portions, a grooved block mounted upon the tie and having apertured projections passing through the apertures in the flange of the tie, a locking member having a grooved arm adapted to engage the groove in said block, an integral finger passing through the apertures in said projections of the block and the web of the tie and adapted to hold the flange of a rail upon said block, as set forth.

4. A means for fastening railway rails to ties comprising, in combination with a tie having apertured flange and web portions, a grooved block mounted upon the tie and having apertured projections passing through the apertures in the flange of the tie, a locking member having a grooved arm adapted

to engage the groove in said block, and an integral finger for engagement with the apertures in the ends of the projections of said block and the web of the tie, the base portion of said finger being inclined and in contact with the under beveled surface of the flange of the tie, as set forth.

5. A means for fastening railway rails to ties comprising, in combination with a tie having apertured flange and web portions, a grooved block mounted upon the tie and having apertured projections passing through the apertures in the flange of the tie, a locking member having a grooved arm adapted to engage the groove in said block, an integral finger for engagement with the apertures in the ends of the projections of said block and the web of the tie, the base portion of said finger being inclined and in contact with the under beveled surface of the flange of the tie, and means for holding said member in a locking relation, as set forth.

In testimony whereof we hereunto affix our signatures in the presence of two witnesses.

EDWARD TIMOTHY FORD.
FRANK FORD WASSAM.
